UNITED STATES PATENT OFFICE

2,266,202

AIR CONDITIONING SYSTEM

Charles E. Heinkel, Portland, Oreg., assignor to
Minneapolis-Honeywell Regulator Company,
Minneapolis, Minn., a corporation of Delaware

Application June 5, 1940, Serial No. 338,937

14 Claims. (Cl. 236—91)

This invention relates to heating and air conditioning systems wherein fresh air from outdoors is passed over a steam heating coil or other heating medium. When the supply of steam or other heating substance to such a coil is modulated, condensate or other partially cooled media may collect in the coil, and when the temperature of the outdoor air is below 32° the condensate or other media may freeze and fill up the coil with ice causing it to crack. This is apt to happen when the supply of steam or media has been modulated down to a small amount insufficient to keep all parts of the coil above freezing. If the supply of steam or other media is controlled in an on and off manner there will be sufficient steam or media in the coil when there is condensate or other cooled media present to prevent it from freezing.

An object of the invention is to control a heating coil or other heating medium in a system of the type above described in a manner to prevent freezing of condensate or other cooled heating media therein.

Another object is to prevent freezing of condensate or partially cooled heating media in a steam heating coil or other heating medium the supply of media to which is ordinarily modulated, by controlling the supply of media in an on and off manner when the temperature of the air to be heated is below freezing.

Another object is to provide freeze-up protection in a heating system wherein outdoor air is heated by a steam coil or other heating medium to which the supply of media is normally modulated by controlling the media supply in an on and off manner when the temperature of the outdoor air is substantially freezing.

Another object is to provide a heating system having means for passing outdoor air over a steam coil or other heating medium wherein the supply of media is normally modulated by a thermostat and is controlled in an on and off manner when the temperature of the air passing through the coil or heating medium is low enough so that there is danger of freezing condensate or partially cooled media in the coil.

For a more complete understanding of my invention and knowledge of its advantages reference may be had to the following detailed description and annexed drawing wherein,

Figure 1 represents diagrammatically a heating system employing a steam coil and having electrical controls therefor embodying my invention.

Figure 2 represents diagrammatically a similar system employing pneumatic controls.

Referring to Figure 1 of the drawing a portion of an air conditioning system for a building is represented, the system being of the type wherein outdoor air is introduced into the building to be heated and a part of the heated air is recirculated after having been delivered to the spaces to be heated. Numeral 10 designates an air duct 10 which communicates with the outdoor air and disposed in this air duct is a steam heating coil generally indicated at 11. The duct 10 communicates with the intake side of a motor driven fan 12, the discharge of the fan being connected to a duct 13 which conveys heated air to the various spaces to be heated. Numeral 14 designates a duct for recirculating air which communicates with the duct 10 to the left of the steam coil 11 so that a mixture of fresh and recirculated air is passed over the steam coil.

The supply of steam to the coil 11 is controlled by a steam valve 15 which is of the type which may be modulatingly adjusted to various positions. The steam valve 15 is controlled by a proportioning type of control system, this type of control system being well known in the art and being disclosed and described in detail in the patent to D. G. Taylor No. 2,028,110 to which reference is had. The proportioning system includes a proportioning motor 16 which operates the valve 15 and a proportioning type thermostat generally designated at 17. The thermostat 17 includes a bimetal element 18 arranged to actuate an arm which sweeps over a resistance 20 as the temperature affecting the element 18 varies. As in the Taylor patent the proportioning motor 16 drives a rebalancing potentiometer generally designated at 21, this potentiometer being illustrated diagrammatically as comprising an arm 22 on the shaft of the motor 16 which sweeps over a resistance 23 as the shaft of the motor is rotated. The ends of the resistance 20 of the potentiometer thermostat are connected to the proportioning motor by wires 25 and 28 and the element 18 of the thermostat is connected to the proportioning motor by wire 31, the connections between the thermostat and the motor corresponding to those of the Taylor patent. The ends of the resistance 23 are connected to wires 25 and 28 by wires 33 and 35, respectively. Normally in proportioning control systems of the type disclosed, the slider of the rebalancing potentiometer is connected to the wire which leads from the thermostat to the proportioning motor. In my arrangement I have provided a

switch whereby the slider of the rebalancing potentiometer may be disconnected so as to render it ineffective. Numeral 37 designates generally a temperature responsive switch device which comprises a bellows element 38 connected to a temperature responsive bulb 39 which is disposed in the path of fresh air being admitted to the conduit 10. The bulb and bellows and connecting means are filled with a volatile liquid so that the bellows contracts and expands in response to 10 temperature changes affecting the bulb, and the bellows actuates a pivoted switch arm 40 which carries a mercury switch 41. Normally the mercury switch 41 is tilted so that the electrical circuit is completed but when the temperature affecting the bulb 39 drops to a predetermined minimum such as 32° F., the mercury switch 41 is tilted and the electrical circuit is broken. The slider 22 of the rebalancing potentiometer is connected to the mercury switch 41 by a wire 42 20 and the mercury switch is connected to wire 31 by a wire 43 so that when the mercury switch is tilted so that the electrical circuit is broken, the slider of the rebalancing potentiometer is disconnected and the rebalancing potentiometer has no 25 effect on the proportioning system.

Numeral 45 designates generally an additional temperature responsive controller comprising a slider 46 arranged to sweep over a resistance 47, the slider 46 having an integral arm 48 at right angles thereto which cooperates with an expandable and contractible bellows 49 which is adapted to move the slider 46 over the resistance 47. The bellows 49 communicates with a bulb 50 by means of a tube, the bulb 50 being disposed in the path of air being discharged from the fan 12. The bellows and bulb are filled with a volatile liquid so as to cause the bellows to expand and contract in response to changes in temperature affecting the bulb 50. The ends of the resistance 47 are connected to the wires 25 and 28 by wires 52 and 54, respectively, there being a resistance 53 in wire 54 so that the resistance 47 is connected in parallel with the resistance 20 as is the resistance 23. The slider 46 is connected to the wire 31 by a wire 56. Normally the slider 46 is at the left end of resistance 47 so that the controller 45 has no effect upon the proportioning system. Resistance 53 is equal to resistance 47 so that when slider 46 is at the left end of resistance 47 the controller 45 causes no unbalancing of the circuit. Whenever the temperature affecting bulb 50 drops below a predetermined minimum the bellows 49 is contracted sufficiently to cause the slider 46 to move to the right along resistance 47, the effect of this being to move the valve 15 in opening direction as will presently be described, the controller 45 serving as a low limit controller to maintain the discharge air temperature above a predetermined minimum.

Normally the proportioning system so far described operates in the manner of that disclosed in the Taylor patent. When the temperature is at the desired value in the space being heated the thermostat 17 has the arm or slider 18 at the mid point of resistance 20. If the temperature should fall the thermostat moves the slider 18 to the left along resistance 20, thus unbalancing the voltage drops existing between wires 25 and 31 and between wires 28 and 31. This movement of slider 18 to the left along resistance 20 causes the motor 16 to operate in a direction opening the valve 15 to increase the supply of steam so as to cause the temperature to come back to normal. When the system has thus been unbalanced

5 by movement of the slider, consequent movement of the rebalancing potentiometer 21 rebalances the system as described in the Taylor patent for stopping the motor when the valve position corresponds to the position of slider 18 on resistance 20. If the slider 19 of the thermostat 17 moves to the right along resistance 20 the motor 16 is operated in the opposite direction to move valve 15 in closing direction.

As pointed out above whenever the temperature affecting bulb 50 drops below a predetermined minimum the slider 46 is moved to the left along resistance 47, this movement having the same effect as movement of slider 18 to the left along resistance 20 inasmuch as it reduces the voltage drop between wires 25 and 31. Thus whenever the temperature affecting bulb 50 falls below a predetermined minimum the motor 16 is operated in a direction to open valve 15 so as to increase the supply of steam irrespective of thermostat 17 whereby the air being delivered to the heated spaces never falls below a predetermined temperature.

In a system of the type which I have disclosed the temperature of the outdoor air being delivered through the conduit 10 may be low enough to freeze condensate before it reaches the outlet of the coil. Particularly at times when the steam valve 15 has been modulated to a nearly closed position such that only a very little steam is being admitted to the coil 11, the condensate is very apt to freeze because of the small amount of steam being admitted to the coil, the amount of steam being admitted being too small to keep all parts of the coil above freezing temperatures. In order to obviate this undesirable condition wherein the steam coil might become entirely filled with ice, in my arrangement whenever the temperature of the outdoor air passing bulb 50 falls below a predetermined minimum the electrical circuit at switch 41 is opened and the rebalancing potentiometer is rendered inoperative. Under these circumstances whenever the slider 18 of thermostat 17 moves out of mid position the motor 16 is started in one direction or the other and inasmuch as the rebalancing potentiometer is now ineffective to rebalance the unbalanced condition produced by the thermostat 17 the motor 16 will continue operating until the valve 15 40 is fully opened or closed. It will be seen therefore that under these circumstances the thermostat 17 now controls the valve 15 in an on and off manner, the valve either being fully opened or closed depending upon which side of the mid point of resistance 20 the slider 18 deviates to. Thus when the outdoor temperature is low enough to cause switch 21 to break the electrical circuit the steam coil 11 is supplied with the maximum amount of steam or else the supply of steam is cut off entirely. Thus there is never a condition wherein there is only a very small amount of steam being admitted to the coil such that condensate would freeze in the unfilled portion of the coil.

Those skilled in the art will appreciate from the foregoing description that I have provided a very simple means for providing what is called freeze-up protection for steam coils or other heating mediums and yet wherein the advantages of modulating control may be enjoyed under normal conditions when the temperature of the outdoor air is not too low.

Referring to Figure 2 I have disclosed the same heating system utilizing a similar manner of control but wherein the controls are of a pneu-

matic type rather than of an electrical type as in Figure 1, like numerals designating like parts in both figures. In Figure 2 the valve 115 controlling the supply of steam to the coil 11 is of a pneumatic type being adjustable to various positions depending upon the pressure in a bellows element 116 which is connected to the stem of the valve.

Numerals 114 designates a pipe leading to a source of air supply which in this type of control system is normally at a pressure of 15 lbs. per sq. inch.

Numerals 150 designates a pneumatic thermostat of known type responsive to the temperature in discharge duct 13 of fan 12, this thermostat controlling a bleed port in the usual manner.

Numerals 120 designates a pressure operated three-way valve comprising a valve element 121 cooperable with oppositely disposed seats 122 and 123. Air may be communicated to the valve chamber of the three-way valve 120 through pipes 124 and 125 and air may be discharged from the valve chamber through a pipe 126. The three-way valve has its stem connected to a pressure responsive element 127 which is of a type which operates at a predetermined pressure to shift the three-way valve from one position to the other with a snap action. In the position of the three-way valve shown, the valve element 121 is in engagement with the seat 122 whereby there is communication between the pipes 125 and 126. Whenever the pressure element 127 is subjected to a predetermined pressure the valve is operated to place the valve 121 in engagement with the seat 123 so as to provide communication with the pipes 124 and 126.

Numerals 139 designates a pneumatic type thermostat similar to the thermostat 150 and responsive to the temperature of the outdoor air being admitted to the conduit 10. Numeral 128 40 designates a manually adjustable needle valve and numeral 129 designates a pressure responsive valve controlling a bleed port 130, the valve being operable by a pressure element 131. Element 131 is of a type which operates valve 129 to either close or open port 130 with a snap action.

Pressure at the supply value of 15 lbs. per sq. inch is communicated to the thermostat 139 through a pipe 132 and the thermostat 139 controls its bleed port so as to bleed off a certain amount of air so as to reduce the pressure, and air at the reduced pressure is communicated from the thermostat 139 to the pressure element 127 by the pipe 133. Similarly air at 15 lbs. pressure is communicated from pipe 114 to the thermostat 150, pipes 134 and 135, and the thermostat 150 controls its bleed port whereby air is bled off at a given rate depending upon the temperature affecting the thermostat 150, and the air at reduced pressure is then communicated to the three-way valve by the pipes 136 and 125. Air at reduced pressure from the thermostat 150 is also communicated to the pressure element 131 through pipes 136 and 140. Air from the supply pipe 114 is communicated through the pipe 134, pipe 141, needle valve 128, pipe 142 and pipe 124 to the three-way valve 120.

When outside temperature is above 32° F., the thermostat 139 causes the three-way valve 120 to be in the position shown. Under these circumstances the discharge duct thermostat 150 controls the pressure being communicated to the operator 116 of valve 115, the thermostat 150 governing this pressure in accordance with the temperature in the discharge duct whereby the 75

valve 115 is positioned in accordance with the temperature in duct 13. Thus the valve 115 is modulated to control the supply of steam in the same manner as in the previous embodiment.

5 When the temperature of the outdoor air being admitted to the conduit 10 drops to a low value such might cause freezing of the condensate in the coil 11, the thermostat 139 will have adjusted its bleed port so that the pressure communicated to element 127 through pipe 133 will be such as to cause the three-way valve 120 to be operated to its opposite position placing pipe 124 in communication with pipe 126 and cutting off communication between pipes 125 and 126. Thermostat 150 will now obviously not be able to control directly the valve 115. Pressure will now be communicated from the source 114 through the needle valve 128 and pipes 142, 124 the three-way valve 120 and pipe 126 to the operator 116 of the valve 115 so that the valve 115 will be moved to closed position. As a result of valve 115 now being moved to closed position the temperature in discharge duct 113 will drop slightly, and at a predetermined temperature affecting the thermostat 150 this thermostat will have adjusted its bleed port so as to lower the pressure in pipes 136 and 140 to such a value that the element 131 will be operated to move the valve 129 away from the bleed port 130. When 20 the valve 129 is moved away from the bleed port 130 the pressure in pipes 142 and 124 is of course immediately released and therefore inasmuch as there is then no appreciable pressure being communicated to the operator 116, the valve 115 will be moved back to open position. The thermostat 150 operates at a predetermined temperature to cause the valve 129 to either close the bleed port 130 or fully open it. When the bleed port 130 is closed the full pressure of the air supply source is communicated to the operator 116 for closing valve 115 and when the valve 129 is moved away from the bleed port 130 the pressure in the pipes beyond the needle valve 128 is immediately released so that there is no pressure communicated to the operator 116 so that the valve 115 is fully open. Thus in this manner when the three-way valve 120 is in the opposite position to that in which it is shown in Figure 2 the thermostat 150 controls the valve 115 in an on-off manner or in other words, the valve 115 is either fully opened or fully closed. Thus it will be seen that the operation of the mechanism of Figure 2 is substantially the same as that of Figure 1 except that the discharge duct thermostat is in sole control of the valve 115.

60 The two representative embodiments of my invention which I have disclosed are merely illustrative of forms which it may take and of types of control equipment which may be utilized for carrying out the invention. My invention is not to be limited by my disclosure but only by the appended claims.

I claim as my invention:

65 1. In a heating system for a building in combination, means comprising a heat exchanger, means for passing outdoor air in heat exchange relation with said heat exchanger, means for controlling the heating media supply and a thermostat for variably adjusting the heating media control means position, and means responsive to the temperature of air passing to the exchanger cooperating with said control means for modifying the action of said last means whereby said heating media control means is operated in an on-and-off manner when the temperature of the

air passing to the heat exchanger is below freezing.

2. In a system for heating outdoor air for use in a building, in combination, a heat exchanger, means for passing outdoor air over said heat exchanger to be heated thereby, valve means controlling the media supply, means responsive to the temperature of heated air for modulating the position of the valve means, and means responsive to the temperature of outdoor air cooperably associated with said modulating means whereby when the outdoor air temperature is below freezing said first mentioned temperature responsive means controls the valve in an on-and-off manner.

3. In a system for heating outdoor air for use in a building, in combination, a heat exchange means, means for passing outdoor air over said heat exchanger to be heated thereby, valve means controlling the heating media supply, means responsive to the temperature of heated air for modulating the position of the valve means, said modulating means being of a type readily adapted to being converted into a type which operates the valve means in an on-and-off manner, and means responsive to the temperature of outdoor air cooperably associated with the modulating means for converting said modulating means whereby the valve means are operated in an on-and-off manner when the temperature of the outdoor air is below freezing.

4. In a system for heating outdoor air for use in a building, in combination, a heat exchanger, means for passing outdoor air over the heat exchanger to be heated thereby, valve means controlling the heating media supply, means responsive to the temperature of heated air for modulating the position of the valve means, means responsive to temperature of air discharged from said heat exchanger also controlling said valve means to maintain a minimum air temperature, and means responsive to the temperature of outdoor air cooperably associated with said modulating means whereby when the outdoor air temperature is below freezing said first mentioned temperature responsive means controls the valve means in an on-and-off manner.

5. In a system for heating outdoor air for use in a building, in combination, a heat exchanger, means for passing outdoor air over the heat exchanger to be heated thereby, valve means controlling the heating medium supply means responsive to the temperature of heated air for modulating the position of the valve means, said temperature responsive means being of the proportioning type including a potentiometer type thermostat and a rebalancing potentiometer, and means responsive to the temperature of outdoor air for disconnecting said rebalancing potentiometer when the outdoor air temperature is below freezing whereby said thermostat operates said valve means in an on-and-off manner.

6. In a system for heating outdoor air for use in a building, in combination, a heat exchanger, means for passing outdoor air over the heat exchanger to be heated thereby, valve means controlling the heating medium supply, means responsive to the temperature of heated air for modulating the position of the valve means, said temperature responsive means being of the proportioning type including a potentiometer thermostat and a rebalancing potentiometer, means responsive to temperature of air discharged from said heat exchanger for maintaining a minimum air temperature, and means responsive to the

temperature of outdoor air for disconnecting said rebalancing potentiometer when the outdoor air temperature is below freezing whereby said thermostat operates said valve means in an on-and-off manner.

7. In a system for heating outdoor air for use in a building, in combination, a heat exchanger, means for passing outdoor air over the heat exchanger to be heated thereby, valve means controlling the heating medium supply, said valve means being of a pneumatically operable type adjustable to various positions, means forming a source of air pressure supply for said valve means, a thermostat controlling a supply of air pressure to said valve means whereby the valve means is modulantly adjusted in accordance with temperature, a pneumatic thermostat responsive to outdoor air temperature and control means whereby said first thermostat either admits pressure to said valve means or wholly interrupts it whereby said valve means is either fully open or closed, said control means being operable in response to said thermostat responsive to outdoor air temperature.

8. In a system for heating outdoor air for use in a building, in combination, a heat exchanger, means for passing outdoor air over the heat exchanger to be heated thereby, valve means controlling the heating medium supply, said valve means being of a pneumatically operable type adjustable to various positions, means forming a source of air pressure supply for said valve means, a thermostat controlling a supply of air pressure to said valve means whereby the valve means is modulantly adjusted in accordance with temperature, means for diverting the air supply for said valve means, means responsive to said thermostat for controlling the diverted air supply in an on-and-off manner so that the valve means are operated in an on and off manner and means responsive to outdoor air temperature controlling the diverting means.

9. In a system for heating outdoor air for use in a building, in combination, a heat exchanger, means for passing outdoor air over the heat exchanger to be heated thereby, valve means controlling the heating medium supply, said valve means being of a pneumatically operable type adjustable to various positions, means forming a source of air pressure supply for said valve means, means forming a first passage for communicating pressure to said valve means, a modulating type thermostat for controlling the pressure in said first passage, a second passage for communicating pressure to said valve means, an on and off device responsive to said thermostat controlling said second passage, and means responsive to outdoor temperature for selectively connecting said passages to said valve means.

10. In combination, a pneumatically driven device, a source of air pressure, a pipe for communicating pressure for operating said device, a thermostat for modulantly adjusting the pressure in said pipe, a second pipe for communicating pressure for operating said device, means responsive to said thermostat for controlling the pressure in said second pipe in an on and an off manner, and means whereby either pipe may be connected to said device.

11. In a heating system for a building, in combination, means comprising a heat exchanger, means for passing outdoor air in heat exchange relation with said heat exchanger, control means comprising a valve controlling the heating medium supply and a thermostat for

modulatingly adjusting the valve position, and means responsive to the temperature of air passing to the heat exchanger associated with said control means whereby the supply of heating medium is controlled in an on-and-off manner when the temperature of the air passing to the heat exchanger is below freezing.

12. In a heating system for a building, in combination, means comprising a heat exchanger, means for passing outdoor air in heat exchange relation with said heat exchanger, control means comprising a valve controlling the heating medium supply and a thermostat for modulatingly adjusting the valve position, and means responsive to the temperature of air passing to the heat exchanger associated with said control means whereby the supply of heating medium is controlled in an on-and-off manner when the temperature of the air passing to the heat exchanger is below freezing, said last named temperature responsive means comprising a control device and a temperature responsive device operatively connected to said control device in such a manner as to cause said control device to always assume one or the other of two controlling positions.

13. In a heating system for a building, in combination, means comprising a heat exchanger, means for passing outdoor air in heat exchange relation with said heat exchanger, 30

control means comprising a valve controlling the heating medium supply and a thermostat for modulatingly adjusting the valve position, and means responsive to a temperature condition indicative of danger of freezing of condensate or partially cooled heating medium in the heat exchanger associated with said control means for causing said heating medium supply to be controlled in an on-and-off manner.

14. In a heating system for a building, in combination, means comprising a heat exchanger, means for passing outdoor air in heat exchange relation with said heat exchanger, control means comprising a valve controlling the heating medium supply and a thermostat for modulatingly adjusting the valve position, and means responsive to a temperature condition indicative of danger of freezing of condensate or partially cooled heating medium in the heat exchanger associated with said control means for causing said heating medium supply to be controlled in an on-and-off manner, said last named temperature responsive means comprising a control device and a temperature responsive device operatively connected to said control device in such a manner as to cause said control device to always assume one or the other of two controlling positions.

CHARLES E. HEINKEL.
